United States Patent Office.

CHARLES T. GILMOR, OF BALTIMORE, MARYLAND.

Letters Patent No. 96,422, dated November 2, 1869.

IMPROVEMENT IN TOBACCO-PRESSES.

The Schedule referred to in these Letters Patent and making part of the same.

I, CHARLES T. GILMOR, of Baltimore, in the State of Maryland, have invented a new and useful Improved Horizontal Press, and, in the following, describe the same.

Nature and Objects of the Invention.

My improved horizontal press is of that class in which lever-power is employed to propel the plunger, consisting essentially of a suitable frame, adapted to receive and support, or provided with a receiver and a reservoir, for the supply of the material thereto, a plunger or follower, arranged horizontally in the frame in line with the reservoir and receiver, and a horizontal lever, so connected with said plunger as, by its reciprocation, to propel the same forward, forcing the material into the receiver, and compressing it to the required extent.

My invention relates to the devices for applying the motion of the lever to the plunger or follower, and for supporting and guiding the two.

It has for its objects the provision of a strong, simple, and easy-working automatic device for the former purpose, and the provision for the support and guidance of the plunger or follower and lever, the freedom from or decrease of friction and strain.

It consists—

First, in the employment, for imparting the motion of the lever to the plunger or follower, of a pair of ratchet-racks, of peculiar construction, attached to the sides of the stem of the plunger, two pull-pawls attached to the lever at suitable points on each side of its fulcrum, and a pair of springs, so arranged, as by engaging with the pawls, at the ends of their backward movements, to force them into mesh with the racks.

Second, in constructing the racks removable, and of increasing thickness from their inner or front ends outward, to provide the increase of strength required, as the operation advances, without unnecessary weight.

Description of Drawings.

In the accompanying drawings—

Figure 1 represents a horizontal section, at $z z$, fig. 2, of a tobacco-prize, illustrating my invention.

Figure 2, a vertical longitudinal section of the same, on the line $y y$, fig. 1.

Figure 3, a vertical transverse section at $x x$, fig. 1.

Figure 4, a horizontal section, on an enlarged scale, of a portion of the stem of the plunger or follower, showing also, in elevation, the pawls in the position which they occupy relatively thereto.

General Description.

In reference to the drawings, similar letters and marks indicate like parts in the several figures.

A A, in the drawings, represent the frame of the press, which may be of any suitable construction;

B, the plunger or follower; and
C, the lever.

f represents the fulcrum of the lever C.

r represent the racks, $p p$, the pawls, and $s s$, the springs, employed to convert the reciprocating vibratory motion of the lever into a progressive rectilinear motion.

The tapering form of the racks r and the graduation of their teeth, are most clearly shown in fig. 4.

1 1, figs. 4 and 5, represent the ledges or flanges, provided at the lower edge of the racks r for the support of the pawls p .

2 2 represent similar, but shorter flanges, preferably provided at the top of the racks, for the support of the teeth, and as an additional retainer for the pawls.

3 represents the additional or intermediate support of the plunger; 3, the friction-roller forming its supporting-surface.

u represents the supporting-truck of the lever; 4 4, its rollers or wheels; and v , its track.

w represents a link, for holding the lever to its fulcrum, and which may also serve to hold the same off of the stem of the plunger, which preferably passes through it at this point, as shown.

o represents a hook for attaching draught to the lever.

D represents the cradle of the prize shown; E, its abutment; F F, uprights, for holding the reservoir and receiving hogsheads in line, being hinged to allow of the introduction and removal of the same; G, the spring-catch, by which the uprights F F are supported; H, the reservoir, and I, the receiving-hogshead; J, the tobacco.

The construction and operation of the parts last referred to, not forming any part of the present invention, need no particular description.

A suitable baling-receiver may take the place of the hogsheads H I, and the adaptation therefor.

The racks r being separate from the body of the stem of the plunger, (the body of the plunger being wood,) may be secured by a dovetail-shape and diagonal bolts or rods 5, as shown.

By making the metallic racks of tapering form, and securing them together by through-bolts, they are caused to cling firmly to the tapering plunger-rod when pressure is applied, so as to relieve from undue strain, the shoulders against which their ends rest, or dispense with the necessity for such shoulders.

The pivots of the pawls p are preferably arranged as near the rear side of the lever as possible, in order to make their movements as nearly as possible parallel with the sides of the stem of the plunger.

The form of the springs s is unimportant, so long as they are adapted to operate as stated. Said springs engaging with the pawls only at the moment they are

to be forced into the rack, all unnecessary friction is avoided, and consequently a great saving in wear and power is accomplished.

The supports τ and τ' may be constructed in any suitable manner.

Operation.

The proper length of stroke of the lever O being fixed, by driving two stakes at proper distance apart, on opposite sides of it or in other suitable manner, and motion imparted to it by means of a team attached to a hook, o , at its outer end, or other suitable means, the pawls p are alternately advanced and retracted, in the former movement, slipping over the inclined backs of the teeth of the racks r , until, coming in contact with the springs s , at the moment they come opposite with the notches of the racks in which they are to engage, they are forced into the same, and their motion then being reversed, they draw the plunger forward by their hold in the racks, by their alternate action rendering this movement nearly continuous.

As the compression advances, the power required to propel the plunger, and consequently the strength required in the racks, increases, and is met by the increasing thickness of the same.

As the power required to propel the plunger increases, the strain on the lever, in imparting the same, also does correspondingly, causing the lever to spring to a greater extent, and consequently the length of stroke imparted to the pawls by it to shorten.

The decrease in the length of the teeth of the racks toward the outer end compensates for this.

During the operation, the plunger is supported on the roller 3 , the lever on the truck u , and the pawls on the flanges 1 , so that all deleterious friction and strain are prevented.

Claims.

I claim, as my invention—

1. The combination, with the plunger or follower B and lever O , of the racks r , constructed with teeth of decreasing length from their inner to their outer ends, pull-pawls p , attached to the lever, on the respective sides of its fulcrum, and springs s , for pressing the pawls into mesh, being so arranged as to engage with them only at the moment they are to be thrown, as herein set forth.

2. The racks r , constructed separately from the plunger B , of increasing thickness from their inner to their outer ends, and applied and secured by diagonal bolts or rods 5 , substantially as shown and described, for the purposes set forth.

To the above specification of my improved horizontal press, I have signed my hand, this 4th day of September, 1869.

C. T. GILMOR.
